PORTABLE DRILL DIE HOLDER

Norman David Hopper, Covina, Calif., assignor of a
fractional part interest to James L. Enloe

Filed Mar. 14, 1974, Ser. No. 451,020

Term of patent 14 years

Int. Cl. D15—99

U.S. Cl. D54—4

Fig. 1.

Fig. 2

Fig. 3.

Fig. 4.

Fig. 5.

FIG. 1 is a front perspective view of a portable drill die holder showing my new design;

FIG. 2 is a right side elevation view thereof, the undisclosed left side is the same in appearance as the side shown;

FIG. 3 is a front elevation view thereof, the undisclosed rear side is the same in appearance as the side shown;

FIG. 4 is a bottom plan view thereof; and

FIG. 5 is a top plan view thereof.

I claim:

The ornamental design for a portable drill die holder, substantially as shown and described.
